UNITED STATES PATENT OFFICE

HERBERT N. VAN FLEET, OF ALVA, OKLAHOMA.

DESIGN FOR A KINDERGARTEN-TABLE.

No. 39,607.

Specification for Design.

Patented Oct. 6, 1908.

Application filed April 17, 1908. Serial No. 427,740. Term of patent 14 years.

To all whom it may concern:

Be it known that I, HERBERT N. VAN FLEET, a citizen of the United States, residing at Alva, in the county of Woods and State of Oklahoma, have invented a new, original, and ornamental Design for Kindergarten-Tables, of which the following is a specification, reference being had to the accompanying drawing, forming part thereof.

The figure is a perspective view of a kindergarten table showing my new design.

The leading and essential feature of the design resides in an oblong rectangular table top having pendent leg standards at the cor-

ners thereof, a continuous horizontal series of drawers arranged below the upper surface of the table top, and a pendent rectangular cabinet pedestal arranged transversely beneath the table top at a point centrally between the opposite ends.

I claim:

The ornamental design for a kindergarten table, as shown and described.
